HOT WATER BOTTLE

James Robert Buchanan, Manchester, England

Application September 16, 1938, Serial No. 230,267

In Great Britain October 7, 1937

1 Claim. (Cl. 150—2.1)

This invention relates to hot water bottles of rubber or the like material, and has for its object to reduce the danger of scalding of the person during the filling of hot water bottles from a kettle or other vessel or tap.

I attain the said object by the means illustrated in the accompanying drawing, wherein—

Figure 1 is a fragmentary side view in section of the upper portion of a hot water bottle.

Figure 2 is a similar view with the stopper removed and a part shown in another position.

Figure 3 is a fragmentary side view in section of a portion of a hot water bottle and illustrates a modification of detail.

Figure 4 is a fragmentary side view in section of a portion of a hot water bottle and illustrates another modification of detail.

Figure 5 is a detached, fragmentary side view in section of a vent tube and illustrates another modification of detail.

Figure 6 is a fragmentary side view in section of the mouth of a hot water bottle and illustrates a further modification of detail.

Referring to the drawing, in the construction shown in Figures 1 and 2, as applied by way of example to a hot water bottle 1 of india rubber having a mouth 2 adapted to serve as a filling funnel, an internally screw-threaded neck 3 into

which a stopper 4 is screwable, and a holding lug 5 on the mouth 2, I provide in the wall of the mouth 2 a hole in which the end 6 of a flexible rubber tube 7 is engaged from the inside of the mouth 2. The end 6 may be permanently

secured in the said hole by vulcanising or other suitable means, or may be detachably held there-in by an annular flange 8 or by two annular flanges 9 and 10, Figure 3, provided on the rubber tube itself or by two annular flanges 11 and

12, Figure 4, provided on a rubber sleeve 13 attached to the tube, the said two flanges holding the wall of the bottle mouth between them round the hole in the said wall. The tube 7 is externally of smaller diameter than the internal diameter of the neck 3. The tube 7 is of sufficient

length to bend in a downward direction and extend downwards through the neck 3 to a short distance beyond the bottom of the neck 3 as shown in Figure 2, its end 14 therefore being capable of lying inside the hot water bottle 1 near the neck 3 thereof. The end 14 has a V-notch

cut into it to form two axial, diametrically situated notches 15 and 16 alternating with two axial, diametrically situated teeth or prongs 17 and 18.

In operation, when it is desired to fill the hot water bottle 1, after removal of the screw stop-

per 4, the tube 7 is bent and its end 14 pushed through the mouth 2 and neck 3 until it is in the position shown in Figure 2 wherein the end 14 is inside the hot water bottle 1. The hot water bottle is then held suspended by the holding lug 5 and hot water is poured into the mouth 2 in the usual manner and flows into the hot water bottle 1 through that portion of the aperture through neck 3 which is not occupied by the tube 7. The air and steam displaced by the water has at all times a free passage through the tube 7 and can therefore escape without bubbling up through the water flowing down the mouth 2 and through the neck 3. The air and steam cannot come into contact with the hand holding the hot water bottle by the lug 5 and the absence of bubbling ensures a complete absence of splashing or shooting back of the water in the mouth 2 and neck 3. The notches 15 and 16 in the end 14 of the tube 7 ensure that the air and steam still have an unrestricted passage into and through the tube 7 even in the event of water, which runs down the exterior thereof, forming a water plug or piston at the lower extremity of the end 14. The teeth or prongs 17 and 18 assist in preventing an accumulation of water on the end 14. Holes or slots 19, Figure 5, may be provided at the lower end of the tube instead of the said notches. When the hot water bottle has been filled, the tube 7 is withdrawn from the neck 3 whilst still remaining attached to the wall of the mouth 2. This leaves the neck 3 free to receive the stopper 4 as shown in Figure 1, and after the stopper has been screwed in, the free part of the tube 7 is disposed within the mouth 2 by coiling it inside the said mouth.

In a modification, instead of providing the hole for the tube in the mouth wall, it may be provided in a lug 20, Figure 6, provided on the lip of the mouth of the hot water bottle in addition to the usual holding lug, and the tube be permanently or detachably connected to the lug 20.

I claim:

A hot water bottle comprising in combination, a mouth forming a filling funnel, a neck for the passage of hot water from the filling funnel to the interior of the hot water bottle, a stopper insertable in the said neck for closing the same, a flexible vent tube permanently connected at one end to the wall of said filling funnel and having said end extending through said wall with its orifice facing in a direction substantially at right angles to the longitudinal axis of the bottle, the tube, when in operative position, being located on the inside of the bottle with its free end ex-

tending from the point of its connection to the funnel through the neck of the bottle, said tube, due to its flexibility, being readily insertable into and readily withdrawable completely from the
5 interior of the said bottle through the said neck without disconnection of any part from the said tube or filling funnel, and the said stopper being

insertable in the said neck only after the free end of the said tube has been withdrawn and therefore the said tube is completely outside the said interior and neck whilst remaining attached to the filling funnel.

JAMES ROBERT BUCHANAN.
